Inventor:

Geo. W. F. Rawson

United States Patent Office.

GEORGE W. RAWSON, OF CAMBRIDGEPORT, MASSACHUSETTS, ASSIGNOR TO
HIMSELF AND MICHAEL HITTINGER.

Letters Patent No. 80,877, dated August 11, 1868.

IMPROVEMENT IN HYDRAULIC PRESSES.

The Schedule referred to in these Letters Patent and making part of the same.

TO ALL WHOM IT MAY CONCERN:

Be it known that I, GEORGE W. RAWSON, of Cambridgeport, in the county of Middlesex, and State of Massachusetts, have invented an Improved Hydraulic Press, to be used in the manufacture of lard-oil, of which the following is a full, clear, and exact description, reference being had to the accompanying drawings, making part of this specification, in which—

Figure 1 is a perspective view of my improved press.

Figure 2 is a vertical section through the centre of the same.

The ordinary press used in the manufacture of lard-oil consists of a stationary bed or platform, upon which are placed the bags of lard, the platen or follower being brought down thereon with the required degree of pressure by means of chains and weights. This press is objectionable, however, as it occupies much space, is heavy, complicated, and expensive, besides requiring much labor to operate it, while the chains, together with the heavy standards at the corners of the press, interfere with the placing of the bags of lard upon the platform, or their removal therefrom.

My invention has for its object to overcome these difficulties, and consists in a press in which the platform for the reception of the lard is placed beneath a hydraulic cylinder, and connected with the piston thereof by means of rods, which serve to raise the platform and give the desired degree of pressure to the lard to extract the oil therefrom, a press so constructed being simple, compact, and powerful, and at the same time easily operated.

To enable others skilled in the art to understand and use my invention, I will proceed to describe the manner in which I have carried it out.

In the said drawings, A represents the lower floor of a room or building, and B the floor above, to which is securely bolted the cylinder C of a hydraulic press, the piston D of which carries a head, E, of small diameter. This head E is connected to a platform, G, beneath the floor B, by means of four rods, a, bent in the form shown, and passing through the corners of a plate or "spreader," H, which serves to steady the rods and retain them at the required distance apart, an opening, b, being made through the centre of the plate, of a size sufficient to enable it to pass freely over the cylinder C', as the platform is raised or lowered by operating the piston.

The extremities of the rods a are secured to the head E and to the platform G by screw-nuts, c d, and by thus securing the rods to the four corners of the platform, it is held rigidly in place, and prevented from being tipped to one side or the other.

The plate or "spreader" H enables me to employ a head, E, of small diameter, which will resist a great amount of strain, whereas, if the plate H were dispensed with, and the rods carried up in a vertical line directly to the head, the latter would require to be of large diameter, and consequently of great weight and corresponding cost, while the liability of its breaking would be much increased.

By thus placing the hydraulic press C D above the platform G, upon which the lard is placed, instead of on the floor beneath it, as has heretofore been customary, the space below the platform is left free and unencumbered, so that a pan (not shown) may be placed on the floor to catch the oil as it drops from the lard, which is contained in bags, as usual, and pressed between the platform G and a plate, I, secured to the under side of the floor B above.

It will be seen that the platform G, with its rods a, occupies very little space, and that the lard may be easily placed upon it or removed therefrom, which is a great advantage where a number of presses are placed side by side.

A press, constructed and arranged as above described, presents many advantages over those heretofore used, as many of the heaviest portions are dispensed with, thereby effecting a great reduction in cost, while it is simple, strong, compact, and easily operated.

Claim.

What I claim as my invention, and desire to secure by Letters Patent, is—

The combination of the platform G, hydraulic press C D, rods a, and plate H, arranged to operate substantially as described for the purpose set forth.

GEO. W. RAWSON.
